UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

ATTACHING MACHINE.

Application filed August 3, 1923. Serial No. 655,518.

My invention relates to attaching machines, as those of the type disclosed in Patent No. 1,382,762, Conner, June 28, 1921, for securing a molded counter to the heel-seat-portion of a turn-shoe.

In such machines, the counter to be attached is held in place upon a block or extension-piece immovably secured upon the under side of the die-block of a nailing apparatus generally resembling the well-known lightning heeler. This block enters between the upstanding sides of a counter, and holds it in a definite relation to a jacked shoe when this has been pushed into the nailing position beneath the die-block. To change the relation between the counter and heel-seat preparatory to attachment, so that the shoe shall be of the correct size, the point at which the jack is arrested is determined by an adjustable back stop. The fixed character of the holding device for the shoe-part to be attached is disadvantageous in some respects, and an object of this invention is to provide, in an attaching machine, for a variation in the position of the part to be attached as it is held by the device, as by changing the effective dimensions of the latter. More specifically, I effect this change both longitudinally and transversely of the element. In connection with the longitudinal alteration, it may be said that adjustment of the back stop of the above-mentioned patent, to determine the location of a counter upon a shoe, is somewhat difficult for the operator, because the adjusting means is at the rear of the machine. I accomplish a similar result by movement of a gage member through the counter-engaging wall of the holding device toward the rear of the machine, with means at the front of said machine, convenient of access by the operator, for adjusting this gage member. The transverse adjustment renders the holding device applicable to such objects as counters, which are without the usual trucks secured to their flanges and spacing the side walls a constant distance apart. With the trucks omitted, as is sometimes desired by manufacturers of turn-shoes, there is nothing to hold the peripheries of the counters in the proper relation to the outer edges of the heel-seat-portions of the shoes, the spring-

clips of the holding blocks tending to press the sides of the counters closer together than they should be when secured upon the shoes. 55 With the transverse adjustment of the holding device, which may be accomplished by gages movable through the engaging walls at the opposite sides of the device, the sides of each counter may be, in all instances, correctly located with reference to the shoe to which it is to be attached.

One of the several embodiments which my invention may assume is illustrated in the accompanying drawings, 65

Fig. 1 being a side elevation, with parts in section, of the portions of a counter-attaching machine more closely co-operating with the work;

Fig. 2, an enlarged front elevation of the 70 center of the die-block and counter-holding block;

Fig. 3, a central vertical longitudinal section through the counter-holding block; and

Fig. 4, a full transverse section there- 75 through on the line 4—4 of Fig. 3.

There appear in the drawings only those portions of a counter-attaching machine which are in direct association with the elements of the present invention. These include a die-block 10 mounted upon a frame 12 and having in it vertical openings 14 to receive the attaching nails or tacks. Entering these openings are drivers 16 depending from a top grit 18 carried by vertically reciprocatory side rods 20. In horizontal ways 22, carried by the usual pressure-applying mechanism, is a jack 24, shown as having upon it a lasted shoe S. This jack is movable in the ways from its outer position, in which the work is placed upon it, to that illustrated in Fig. 1, in which the heel-seat-portion of the jacked shoe is aligned with the openings 14 in the die-block. Fixed in place upon the under side of the die-block and having openings 26 registering with the openings 14 is a counter-holding block or extension-piece 28. The periphery of this holding block has substantially the horizontal contour of a counter which is to be attached, having a 100 side wall 30 curved similarly to the interior of the counter, and a vertical breast-wall 32, which comes between the spaced ends of the counter. Spring-clips 34, 34, projecting

over the wall 30 adjacent to the breast-wall and adjustably mounted upon a transverse screw 36, press toward the block an applied counter and serve to retain it in place. A 5 spring-clip 37 depends from the die-block at the back of the block 28, for engagement with the counter at this point. To permit this clip to co-operate properly with a gage member hereinafter described, it should possess sufficient yieldability to allow the counter to be forced rearwardly to some extent. Mounted to move with the jack is a back stop 38 carried upon the upper extremity of a rod 40. This stop contacts with the rear 10 of the jacked shoe-upper outside the edge of the sole to correctly locate the shoe beneath the block for co-operation with the counter which is to be nailed upon it. The rod 40 is engaged by the head of a screw 42 threaded 15 horizontally through a bracket secured to the frame and adjustable by means of a nut 44 rotatable between spaced walls of the bracket. By turning this nut to advance or retract the screw, the position of the back stop, and consequently the relation of the engaged shoe to the counter, may be 20 changed.

The counter-holding block 28 is shown as formed in two sections horizontally divided, 25 there being in one of these sections, preferably the upper, a groove extending centrally and longitudinally of the block. Arranged to slide in this groove is a bar 46 having projecting through the rear of the curved wall 30 of the block an end 48 furnishing a back gage. Upon the forward extremity of the bar is an upstanding lug 50, in which is a horizontal, threaded opening to receive 30 a screw 52. This screw carries flanges 54, 54 rotatable upon opposite sides of a wall 55 of the block. The head 56 of this screw lies outside the breast-wall 32, where it is directly in front of the operator and entirely clear of the work. Ordinarily, the 35 initial adjustment to determine the relative longitudinal relation between the jacked shoe and the counter which is to be secured to it would be provided for by the adjustment of the back stop 38. The rear edges of the shoe-soles, however, vary considerably in their extension against the portion of the upper which contacts with the back stop, because, being in temper, they are 40 likely to be deformed. If, having brought the heel-seat-portion of the shoe beneath the block 28 and the counter which it supports, the operator observes that the point of attachment of the counter will not be far enough back on the sole, a condition which 45 50 would make the resulting shoe shorter than the true size, he can remedy this by adjustment of the gage-bar 46. To do this, he has only to turn the readily accessible head 56, forcing out the end-portion 48, so that the 55 counter is displaced somewhat rearwardly

upon the block 28 until such counter is correctly located over the heel-seat. The attaching operation having been effected, the operator may return the gage to its normal position.

Below the bar 46, adjacent to the breast-wall 32, and extending transversely of the block 28, is a horizontal bore, in which are mounted opposite tubes 58, 58 having their closed, rounded ends 60 normally lying just 70 outside the block-wall 30 to act as side gages. The interiors of these tubes are oppositely threaded to receive similarly threaded portions of a screw 62. Extending into the block, through the breast-wall 32, is a slot lying between the gage-tubes 58 and receiving a flange or finger-piece 64 secured at the center of the screw 62. The periphery of this finger-piece projects beyond the breast-wall, and is preferably nubled so that 75 it may be turned conveniently by the operator. By rotating the screw 62 by means of its finger-piece, the ends of the gage-tubes may be projected from or drawn into the 80 openings through the wall 30 of the block, 85 furnishing adjustable abutments against which the clips 34 may clamp the supported counter with its sides properly spaced to agree with the outside of the heel-seat-portion to which it is to be attached. On account of the position of the finger-piece 64, 90 this adjustment of the ends 60 of the gage-tubes may be varied readily by the operator when the sizes of the counters change.

Having described my invention, what I 100 claim as new and desire to secure by Letters Patent of the United States is:

1. In a machine of the class described, a holding device arranged to enter the interior of an object to be attached, retaining means 105 acting upon the exterior of the object, and means engaging the interior of the object and arranged to vary the position of said object as it is held by the device.

2. In an attaching machine, a holding device arranged to enter the interior of an object to be attached, pressure means co-operating with the exterior of the object, and means arranged to vary the effective dimensions of the device at the portions co-operating with the object.

3. In an attaching machine, a holding device arranged to enter the interior of an object to be attached, a plurality of pressure members acting upon the exterior of the object, and means arranged to vary in a plurality of directions the effective dimensions of the device at the portions co-operating with the object.

4. In an attaching machine, a holding device arranged to enter the interior of an object to be attached, pressure members acting upon the object at the sides and rear of the device, means arranged to vary the effective holding dimensions of the device trans-

- versely of the object, and means arranged to vary such dimensions longitudinally of the object.
5. In an attaching machine, a holding device having a wall for co-operation with an object to be attached, a gage movable through the wall, and means arranged to vary the extent of projection of the gage from the wall.
10. 6. In a counter-attaching machine, a jack, a counter-holding device co-operating therewith, and means acting upon the inside of a counter and arranged to change the position of said counter upon the holding device with relation to the heel-seat-portion of a jacked shoe.
15. 7. In a counter-attaching machine, a jack, a counter-holding device co-operating therewith, and means arranged to act upon the inside of a counter held by the device and to change the position of said counter upon the holding device both longitudinally and transversely of a jacked shoe.
20. 8. In a counter-attaching machine, a counter-holding device, yieldable counter-retaining means, and means arranged to move a counter held by the device relatively to said device against the retaining means.
25. 9. In a counter-attaching machine, a counter-holding block, a gage member projecting from said block within the counter held thereby, and means arranged to move the gage member upon the block.
30. 10. In a counter-attaching machine, a counter-holding block, a plurality of gage members movable upon the block, and means arranged to move the gage members independently of one another.
35. 11. In an attaching machine, a holding device arranged to enter the interior of an object to be attached, and means arranged to vary the effective dimensions of the device longitudinally of the object.
40. 12. In an attaching machine, a holding device having a wall for co-operation with an object to be attached, a gage member movable through the wall at the rear of the machine, and means situated at the front of the machine and arranged to move the gage member.
45. 13. In a counter-attaching machine, a jack, a counter-holding device co-operating therewith, and means carried by the device and arranged to vary longitudinally of a jacked shoe the position of a counter thus held.
50. 14. In a counter-attaching machine, a counter-holding block, and a gage member movable through the rear portion of the block.
55. 15. In a counter-attaching machine, a counter-holding block, a gage member movable through the rear portion of the block and having at its opposite end a threaded portion, and a screw extending through the breast-wall of the block and engaging the threaded portion.
60. 16. In an attaching machine, a holding device arranged to enter the interior of an object to be attached, means for forcing the object toward said device, and means arranged to vary the effective holding dimensions of the device transversely of the object.
65. 17. In an attaching machine, a holding device having a wall for co-operation with an object to be attached, and gages movable through the wall at opposite sides of the object.
70. 18. In an attaching machine, a holding device having a wall for co-operation with an object to be attached, gages movable through the wall at opposite sides of the object, and means arranged to vary simultaneously the extent of projection of the gages through the wall.
75. 19. In a counter-attaching machine, a jack, a counter-holding device co-operating therewith, and means arranged to vary the relation of the sides of the counter engaged by the device to the sides of the heel-seat-portion of a jacked shoe.
80. 20. In a counter-attaching machine, a counter-holding device, and members movable through opposite sides of the device into contact with a counter held thereon.
85. 21. In a counter-attaching machine, a counter-holding block, a pair of gage members movable in the block and having oppositely threaded portions, and a screw engaging said threaded portions and being rotatable in the block.
90. 22. In a counter-attaching machine, a counter-holding block, a pair of gage members movable in the block adjacent to the breast-portion and being oppositely threaded, a screw rotatable in the block in engagement with the opposite threads of the gage members, and a finger-piece carried by the screw and projecting through the breast-portion of the block.
95. 23. In a counter-attaching machine, a counter-holding block, and a back gage and a side gage movable in the block.
100. 24. In a counter-attaching machine, a counter-holding block, a back gage and a side gage movable in the block, and means situated at the breast-portion of the block for adjusting the gages.
105. In testimony whereof I have signed my name to this specification.

ELMER R. POPE.
